UNITED STATES PATENT OFFICE.

MICHAEL COLLINS, OF JOPLIN, MISSOURI, ASSIGNOR OF ONE-HALF TO J. L. ALLHANDS AND R. E. DAVIS, BOTH OF JOPLIN, MISSOURI.

FIFTH-WHEEL CONNECTION.

Application filed March 6, 1925. Serial No. 13,603.

To all whom it may concern:

Be it known that I, MICHAEL COLLINS, citizen of the United States of America, residing at Joplin, in the county of Jasper and State of Missouri, have invented certain new and useful Improvements in Fifth-Wheel Connections, of which the following is a specification.

This invention relates to new and useful improvements in fifth wheel connections.

The object of the invention is to provide a turning connection between the front running gear and the body or frame support of a wagon body, road scraper or other vehicle, capable of compensating a tilting movement either of the body or the axle.

A particular object is to provide a turntable mounted to rock laterally on a draft-table attached to an axle, whereby the line of draft is in substantially the same horizontal plane as the axis of the hinge of the turn-table and the draft table.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a side elevation of a fifth wheel connection constructed in accordance with my invention,

Fig. 2 is a front elevation of the same,

Fig. 3 is a longitudinal vertical sectional view, and

Fig. 4 is a plan view.

In the drawings the numeral 10 designates a front axle which may be of any approved construction and is preferably square in cross-section. A horizontal draft table or plate 11 is mounted on the axle and secured thereto by clips 12. The axle extends transversely under the rear portion of the table, which forms a turntable support. Disposed longitudinally of the center of the said rear portion of the table is a pair of spaced ears 13; a pair of spaced ears 14 are disposed transversely across the front portion of the table at substantially right angles to the ears 13. This front portion of the draft table extends a substantial distance forwardly from its rear turntable supporting portion and forms a draft coupler portion, as hereinafter described.

The bottom plate 15 of a turn table has depending ears 16 disposed diametrically and spaced to straddle the ears 13. A hinge pin 17 passes through the ears 13 and 16 and hinges the plate 15 on the table 11, so that either the table or the plate may rock relatively of each other. A king pin or pivot stud 18 extends vertically from the center of the plate 15.

The upper circular plate or member 19 of the turn table rests upon the plate 15 and has a central upstanding sleeve 20 integral therewith through which the pin 18 extends. The pin projects above the upper end of the sleeve and receives a washer 21 which rests upon the sleeve. A cotter key 22 passing through the pin bears on the washer and prevents upward displacement of the sleeve on the pin.

A supporting arm 23 formed integral with the sleeve and plate 19 extends rearwardly and upwardly and may be attached to a wagon body, road scraper, grader or other vehicle with which the connection is used. Radial brace webs 24 extend from the plate 19 up to the sleeve at substantially equally spaced points around the table with relation to support 23. It will be seen that the plate 15 and the pin 18 together with the table 11 and front 10, may turn freely in the sleeve 20 and under the table 19. Also through the hinge connection the parts may tilt laterally.

Draft connections 25 are hinged to the ears 14 and in turn are fastened to a tongue 26. It will be noted that the axis of the bolts 27 connecting the parts 14 and 25 is in the same horizontal plane (Fig. 3) as is the axis 17 connecting the two tables. This is one of the important features of the invention because the line of draft being in the same plane as the hinge connection assures an even forward pull on the tables. It will be seen that where the line of draft is above the hinge pin the tendency is to lift the draft table and swing the axis forwardly, thus making an unequal strain; and where the line of draft is below said pin the action is reversed.

Various changes in the size and shape of the different parts, as well as modifications and alterations, may be made within the scope of the appended claims.

What I claim is:

1. In a fifth-wheel, a draft table of uni-

- 5 tary formation and having a rear turntable supporting portion and a front draft coupler portion integral therewith, a transverse axle disposed beneath and fixed to said turntable supporting portion, a turn-table mounted on said turntable supporting portion to tilt laterally on a horizontal axis extending longitudinally of the draft table, and a draft element pivoted to the front
- 10 draft coupler portion of the draft table to swing vertically on a horizontal axis transverse to the draft table, the said axes of the turntable and draft element being so disposed as to lie substantially in the same
- 15 horizontal plane.
2. In a fifth-wheel, a draft table comprising an oblong rectangular plate having a rear turntable supporting portion and a front draft coupler portion, a transverse
- 20 axle extending beneath and fixed to the turntable supporting portion of the draft table, a pair of apertured ears extending upwardly from the turntable supporting portion in the center line thereof and in
- 25 front and rear of the vertical plane of the axle, a turntable, the base member of which is provided with a series of three depending apertured ears lying in front and in rear and between the first-mentioned apertured ears, a hinge pin extending horizontally through said apertured ears and hingedly supporting the turntable to tilt laterally on a horizontal longitudinal axis,

35 a pair of spaced apertured ears projecting upwardly from the draft coupler portion of the draft table on opposite sides of the center thereof and beyond opposite sides of the center line of said horizontal transverse axis, a draft element, and a hinge pin passing through the last-mentioned apertured ears 40 and hingedly connecting said draft element to the draft table so as to swing vertically on a horizontal transverse axis, the said axes of the turntable and draft element being disposed substantially in the same horizontal 45 plane.

3. In a fifth wheel, an axle, a horizontal draft table mounted at its rear portion on the axle, hinge ears extending upward from and disposed longitudinally of the draft 50 table relatively on each side of the axle, up-standing draft ears at the front of the draft table at right angle to the table ears the said hinge ears and draft ears being arranged substantially in the same horizontal plane, a turn-table plate having depending ears hinged to the draft table ears, a king pin on the said plate, a second turn-table-plate mounted to rotate on the first plate, a draft element hinged to the draft 55 ears at the front of the draft table, and a support extending from the second plate.

In testimony whereof I affix my signature.

MICHAEL COLLINS.
